UNITED STATES PATENT OFFICE

165,686

CONTROL KNOB FOR A FOOD MIXER OR THE LIKE

Ivar Jepson, Oak Park, Ill., assignor to Sunbeam Corporation, Chicago, Ill., a corporation of Illinois

Application January 16, 1951, Serial No. 13,828

Term of patent 14 years

(Cl. D44—1)

To all whom it may concern:

Be it known that I, Ivar Jepson, a citizen of the United States, residing at Oak Park, in the county of Cook and State of Illinois, have invented a new, original, and ornamental Design for a Control Knob for a Food Mixer or the like, of which the following is a specification, reference being had to the accompanying drawing, forming part thereof.

In the drawing:

Figure 1 is an end elevational view of a control knob for a food mixer or the like, embodying my new design;

Fig. 2 is a side elevational view; and

Fig. 3 is a top plan view.

I claim:

The ornamental design for a control knob for a food mixer or the like, substantially as shown.

IVAR JEPSON.
